TOY DISK PROJECTOR

Robert W. Clauss, Riverdale, N. Y.

Application January 12, 1949, Serial No. 70,409

4 Claims. (Cl. 124—26)

1
This invention relates to pistols for distributing advertising projectiles of the type described in U. S. Letters Patent No. 2,019,894 granted on November 5, 1935, to Max O. Clauss.

This invention is an improvement thereover, and presents a compact structure easy to make and install into a pistol casing.

It is characteristic of these inventions to have an impelling element for discharging a projectile, as a disk on which advertising, educational or entertainment matter is preferably applied, move in a curvilinear or spiral path with respect to a horizontal plane or surface on which the projectile is moved forward in rotating motion, for giving the projectile a force to continue its motion by its own momentum in a straight line for a considerable distance.

The present improvement consists in providing a straight main portion in the impeller rod, adapted to superposed bearings, said impeller rod having a bent portion at right angles to the main portion and a second bent portion at right angles to the first bent portion extending upwardly, with a helical spring surrounding the main portion, fixed at one end, and having its other end moved by the main portion to tension the spring, and a trigger mechanism acting directly on the said last named end of the spring to hold it in tensioned position, or to release said end in order to have the spring exert its stored energy upon the main portion, and operate the upwardly extending portion in its curvilinear or spiral path, to impel a projectile by first engaging it and then releasing itself from the projectile.

The invention includes also an enlarged convolution of the spring to increase its life. The invention includes also the relationship of the spring pressure point on the trigger lever and the pivot of the trigger in one line, substantially perpendicular to the axis of the main portion of the rod.

The invention will be more fully described hereinafter, embodiments thereof shown in the drawings, and the invention will be finally pointed out in the claims.

In the accompanying drawings,

Fig. 1 is a side view of the improved pistol, underlying the invention;

Fig. 2 is a horizontal vertical view taken on line 2—2 of Fig. 1, that is, with the top removed;

Fig. 3 is a vertical section taken on line 3—3 of Fig. 2;

Fig. 4 is a vertical section taken on line 4—4 of Fig. 3;

Fig. 5 is a similar section but only fragmentary of the trigger mechanism of Fig. 3, but now in momentary unlocked position;

2
Fig. 6 is a horizontal section on line 6—6 of Fig. 4; and

Fig. 7 is a detail view of the spring acting on the rod.

5 Similar characters of reference indicate corresponding parts throughout the various views.

Referring to the drawings, a rod 10 has a stem 11 to enable the rod 10 to be rotated in its bearings 12 and 13 forming part of the pistol casing 14.

10 The rod 10 with its bearings is placed in an inclined position, as shown in Fig. 3.

Upon the shoulders 17 and 17a, in which the bearing 13 is arranged, is supported a coiled spring 15, which has one end 16 bent to engage recess 16a of the shoulder 17a of the casing 14 so as to anchor one end of the spring 15. The other end 18 of the spring 15 is bent at right angles to its axis, and passed through an opening 19 of the rod 10 (Fig. 6). When the stem

15 20 11 is rotated, and thereby the rod 10 is rotated, the convolutions are compressed, and the end 18 is engaged by the notch 20 of a lever 21, forming part of a trigger mechanism, which then holds the end 18 against movement. The end 18 may

25 ride freely on the cam portion 21a of the lever 21, until the end 18 engages the notch 20 and is held thereby. The rod 10 then is in the position shown in full lines in Figs. 3 and 4.

To operate the rod 10 by the stored energy on 30 the release of the spring 15, the finger lever 23 of the trigger mechanism, is pressed by a finger of the operator of the pistol, in the usual manner, as known, whereby said lever 23 raises the lever

35 21, the free end of which abuts against the interior surface 24 of the casing 14, to rest there against. When the lever 21 is raised and its notch 20 becomes disengaged from the end 18 of the spring 15, the rod 10 is free to rotate under the forces exerted by the compressed energy

40 of the spring 15, until the rod 10 takes the dotted line position of Fig. 3 and the full line position of Fig. 5.

The rod 10 has a part 30 bent at right angles to its main portion 10a, and in continuation of

45 the part 30 is another part 31, at right angles to the part 30, and extending upwardly, parallel with the axis of the main portion 10a of the rod 10. The end 32 of the part 31 engages a hole in a paper disk, and its curvilinear and spiral movement moves the disk and propels it from the gun, until the end 32 descends while in its circular movement, to disengage itself from the disk, the disk then continuing to move under the force of

50 55 the propulsion described, in substantially the manner shown in U. S. Letters Patent No. 2,019,894.

In making of the spring 15 it is important to

give the spring wire a special curvature as shown at 35 in Fig. 6. It has been found that, if the spring wire is abruptly bent in the usual convolution form, the wire is subjected to too severe a strain and soon disintegrates, but by providing the special turn as at 35, the spring is given a long life. By having the spring 15 bent around the part 17a of the casing and enclosed in the groove or recess 16a when the matching members abut and are joined together, each matching member having such a part or lug 17, 17a, the spring is held in position against movement. As the spring engages the rod, the rod is held against any substantial axial movement, and thus the spring holds the rod in fixed position, upwardly or downwardly. Whatever expansion or compression of the convolutions of the spring may take place upon the axial movement of the rod, the rod is returned by the action of the inherent resiliency of the spring.

The gun casing 14 consists of two matching members 13a and 13b, substantially alike, save for the interlocking lugs 13c, and these matching members 13a and 13b are joined by screws 37 and 38. A hand portion 39 merges into a cylindrical portion 40, and this in turn has forwardly extending parallel portions 41. Abutments 42 and 43, provided with a first pin 44, are spaced from each other to accommodate the elbow lever trigger 23. A coil spring 45 has one end secured by the screw or pin 38 to the matching members and its other end 47 looped around the lever 21, engaging a notch 23a of the lever 21. A slot 48 permits the free movement of the lever 21. Normally, the spring 45 exerts a downward pressure on the lever 21, which pressure must be overcome by the pressure of the finger of the operator in order to raise the lever 21, and release the notch 20 from the end 18 of the spring 15, in order to permit the spring 15 to exert the propelling effect on the disk.

Upon the upper part of the circular portions 40 of the matching members, a plate 50 is secured, to which a spaced plate 51 is secured by screws 52, the depth of the space 53 being slightly larger than the thickness of the paper disk to be propelled. The plate 50 has downward extending projections 56, entering recesses or cutouts 57 in the matching members. These projections extend laterally to engage recesses 57 in the matching members. A spacer 54 is made a part of the plate 50 as shown in Fig. 4, and preferably extends along the length of the pistol barrel to about 55. The perimeter of the plate 50 is spaced from the cylindrical part 40 of the casing (Fig. 4) to enable the free movement of the part 31 of the rod 10 to take place, while the free end 32 moves from its uppermost portion as shown in full lines in Fig. 4 to its lowermost position as shown in dotted line position in Fig. 4, that is, during its propelling action on the disk from its engagement thereof to beyond its disengagement thereof.

It will be noted that the matching members, when joined, provide the bearings for the main part of the rod, and that the support for the upper bearing is engaged by the propelling spring, the other end of which spring engages the rod, with the proximate coil enlarged to provide resiliency securing long life, the main part of the rod extending out of the casing or matching members, to enable the rod to be rotated to tension the spring, with the single bar trigger holding the spring in tensioned position, until the end of the spring is released from the trigger,

enabling the rod to rotate and compel its impelling end to do its work on the projectile. The pressure application point of the spring 15 and the pivot of the trigger lever is on a line substantially perpendicular to the axis of the main part 10a of the rod 10.

The matching members may be readily cast of suitable aluminum, white metal, or the like, or made of plastic material, the spring and impelling rod being both of the utmost simplicity, and the top piece to provide the runway for the disk, may be readily cast of similar material and applied to hold the matching members to complete the pistol.

I wish it to be understood that I do not desire to be limited to the exact details of construction shown and described, for obvious modifications will occur to a person skilled in the art.

I claim:

1. In a toy pistol, having a casing with superposed bearing surfaces, a rod supported by said bearing surfaces and having one end extending outside of the casing, and extending at the upper end of the bearing surface at right angles to its axis, and extending upwardly at right angles to said right-angled part, said last named part being parallel with the axis of said rod, and having its free end serving as an impeller, said bearing surfaces being disposed on a line inclined to the vertical, for enabling the impeller end to partake of a curvilinear helical path in respect to the horizontal on the rotation of the impeller end around the axis of the rod in the bearing surfaces, the combination of a trigger lever pivoted to the casing, a spring to hold the trigger in cocked position, and a torsion spring for the rod having one end anchored to the casing and the other end engaging the rod, and engaging the trigger lever when the torsion spring is energized by the rotation of the rod, said trigger lever when moved to uncocked position away from the end of the torsion spring, releasing said spring and enabling its energy to rotate the rod and move its impeller end in said curvilinear path, for projecting a projectile by said impeller end.

2. The structure of claim 1, in which the rod operating torsion spring has a plurality of convolutions, with the convolution contiguous to the end of the spring engaging said rod and engaging the trigger lever, having a rounded portion forming a space around the rod.

3. The structure of claim 1, in which the pressure point of the rod torsion spring on the trigger lever and the pivot of the trigger are on a line substantially perpendicular to the axis of the main portion of the rod.

4. The structure of claim 1, in which the trigger lever rests against a wall of the casing to prevent the trigger lever from descending.
